(57) **CLAIM**

The ornamental design for an over the counter medicinal container with surface ornamentation, as shown and described.

DESCRIPTION

The present application file contains at least one drawing executed in color. Copies of this patent or patent application publication with color drawing(s) will be provided by the Office upon request and payment of the necessary fee.

FIG. 1 is a perspective view of an over the counter medicinal container with surface ornamentation embodying our new design;

FIG. 2 is a front view thereof;

FIG. 3 is a rear view thereof;

FIG. 4 is right side view thereof;

FIG. 5 is a left side view thereof;

FIG. 6 is a top view thereof;

FIG. 7 is a bottom view thereof;

FIG. 8 is a perspective view of a second embodiment of an over the counter medicinal container with surface ornamentation embodying our new design;

FIG. 9 is a front view thereof;

FIG. 10 is a rear view thereof;

FIG. 11 is a right side view thereof;

FIG. 12 is a left side view thereof;

FIG. 13 is a top view thereof;

FIG. 14 is a bottom view thereof;

FIG. 15 is a perspective view of a third embodiment of an over the counter medicinal container with surface ornamentation embodying our new design;

FIG. 16 is a front view thereof;

FIG. 17 is a rear view thereof;

FIG. 18 is a right side view thereof;

FIG. 19 is a left side view thereof;

FIG. 20 is a top view thereof; and,

FIG. 21 is a bottom view thereof.

Broken lines are included herein for illustrative purposes only and form no part of the claimed design. In FIGS. 1-2 the stippling represents color contrast. In FIGS. 15-16 the medicinal container is lined for color.
